UNITED STATES PATENT OFFICE.

LOUIS AUSTER AND MARIE AUSTER, OF NEW YORK, N. Y.

BATHING CAP.

Application filed November 1, 1924. Serial No. 747,300.

To all whom it may concern:

Be it known that we, LOUIS AUSTER and MARIE AUSTER, citizens of the United States, and residents of New York, in the county of New York and State of New York, have invented certain new and useful Improvements in Bathing Caps, of which the following is a specification.

This invention relates to bathing caps and is more particularly directed to an improvement in that type of device described and claimed in our Patent No. 1,482,723 dated February 5, 1924.

Bathing caps as constructed do not protect the hair or ears of the bather from water and this is due to the fact that the irregular contour of the head more particularly defined by crevices at the points behind the ears and at the nape of the neck permits the ingress of water to the interior of the bathing cap thereby causing saturation of the hair and allowing water to enter the ears. Furthermore, due to the fact that some persons have greater depressions at points adjacent the ears and at the nape of the neck a bathing cap normally constructed in accordance with the device described and claimed in my patent will not always conform to the head in such cases, and it is therefore necessary to take additional precaution to counteract the greater depth of such depression.

It is an object of this invention to provide a device which when incorporated in a bathing cap as a unitary structure will prevent the passage of water to the interior of the cap by not only compensating for the irregular contour but by maintaining portions of the cap within the depression and in close contact with the head.

Another object of the invention is the provision of reinforcing ribs to prevent distortion of the water guards which pocket the ears and protect them against water and pressure.

A still further object of the invention is the provision of a guard incorporated in a bathing cap to protect the ears and hair from water and in which a rib is disposed along the lower periphery of the cap at points where the cap embraces the ears and nape of the neck, the rib decreasing in thickness from points adjacent the ears towards the intermediate portion of the back of the cap whereby the portion of the rib which embraces the nape of the neck will be suffi-

ciently thin to permit the rib to be stretched and forced in close contact with the neck of the wearer.

This invention will be best understood from a consideration of the following detailed description, in view of the accompanying drawing forming a part of the specification; nevertheless it is to be understood that the invention is not confined to the disclosure, being susceptible of such changes and modifications which shall define no material departure from the salient features of the invention as expressed in the appended claims.

In the drawings:

Figure 1 is a view in perspective of a bathing cap showing the guards and protective ribs held in position by straps.

Figure 2 is a view in perspective of a bathing cap showing a modified form of the straps for maintaining a resilient band in position at the periphery of the cap.

Figure 3 is a bottom plan view of the rear portion of the cap.

Figure 4 is a sectional view taken along the line 4-4 of Figure 1.

Figure 5 is a sectional view taken along the line 5-5 of Figure 2.

Referring more particularly to the drawings, 10 designates a bathing cap having an opening adapted to receive the head of a wearer, with the opening at the periphery of the cap being provided with a reinforced member 11 at the front of the cap.

At opposite points on the cap, openings are provided as shown at 12 to receive the ears. Ribs 13 are formed at the periphery of the opening and embrace the ears and are of sufficient height to prevent a cover 14 from pressing upon the ears. The openings 12 and the contour of the ribs are shaped to conform to the ears.

A rib 15 is connected to the rib 13 at the front portion of the ear pocket and extends forwardly but decreasing in thickness until it merges into the member 11 at a short distance from the ribs 13. This rib provides for a reinforcement to prevent distortion of the ribs 13 in front of the ear when the cap has been forced upon the head of the wearer.

A rib 16 has its ends connected to the ribs 13 at points at the rear of the ears and extends along the periphery of the cap at the back. As shown more particularly in Figure 3, the rib is substantially of the

same thickness as the ribs 13 where it joins said ribs, but gradually decreases in thickness until it merges into a rib of uniform thickness throughout its length, having less thickness than the ribs 13, and is adapted to snugly embrace the back of the neck. It will be seen that this rib is therefore more flexible than the ends of the rib so that when the cap is forced down upon the head and the rear portion 17 of the rib 16 is in position, the rib will be stretched to force the cap at this point in close contact with the neck and prevent the seepage of water.

15 Due to the fact that certain persons have greater depressions at the portion of the head which is at the rear of the ears, it is necessary to provide straps 18 which are formed integrally with the covers 14 of the ear pockets and are made sufficiently long that they may be brought down under the chin and there secured in any approved manner. While we have shown the straps 18 formed integrally with the covers 14 the straps may be secured by cementing or by any other well known means. The straps are provided with a plurality of perforations 19 adapted to receive a button 20 whereby the straps are locked together.

20 The ear pockets generally designated by the numeral 21 in Figure 1 are each formed by means of an annular rib 13 secured to the material at the periphery of the opening 12 and provided with a cover 14, but it must be borne in mind that these pockets may be formed by making depressions in the cap of sufficient depth to receive the ears, and while we have described the openings 12 as formed in the cap nevertheless it is to be understood that the cover 14, ribs 13 and the cap 10 comprise a single unitary structure and that the pocket or chamber between the ribs 13 and the cover 14 may be formed in any approved manner to form a receptacle for the ears while the ribs and straps 18 cooperate to prevent the passage of water into the cap and thereby protect the interior of the ears against the injurious effects of water and also to relieve pressure on the ears.

When the ends of the straps are secured together their inner ends where connected to the covers 14 will exert an inward pressure on the portions 24 of the pockets and not only force the pockets in closer contact with the head but will also maintain such a contacting relation that water will be prevented from entering the cap. The straps exert a pressure on the ribs rather than causing a pull on the caps per se so that the ribs 13 will snugly engage the head adjacent the ears and seal the cap against water.

In the form shown in Figures 2 and 5 the strap 18^a is secured as shown at 22 to the

cover 14^a of the ear pocket and at a point which is adjacent the upper end of the pocket so that the resilient and endless band 23 may be received between the covers 14^a and the straps 18^a and be maintained in place particularly during diving. The other elements of the cap are similar in all respects to the elements described for the construction shown in Figures 1 and 4. The band 23 is adapted to be placed over the cap and be maintained adjacent the periphery of the opening of said cap for embracing the forehead and ears and nape of the neck of the wearer in order to maintain the lower ends 24 of the cap in close contact with the head to prevent any possible passage of water.

It will be seen that the strap 18^a not only tends to force the lower end of the pocket into close contact with the head but will also maintain the band 23 against slippage. The shorts ribs 15 which are connected with the pockets 21 and the reinforcement 11 of the cap will prevent distortion of the ribs 13 when the cap has been forced in position.

The straps may be omitted and the endless band employed solely for the purpose of maintaining the pockets against movement in those cases where bathers object to the use of the straps.

What we claim is:

1. A bathing cap made of elastic materials having raised portions adapted to receive the ears of a bather and chin straps connected to the raised ear receiving portions above the inner surface for causing the materials of the bathing cap embracing the portions to snugly contact with head of the wearer by exerting an inward pressure on the raised portions.

2. A bathing cap made of elastic materials having ear receiving openings, ribs encircling the openings, covers connected to the ribs, and chin straps connected to the covers.

3. A bathing cap made of elastic materials having ear receiving openings, ribs encircling the openings, covers connected to the ribs to form pockets for the ears of a bather, and chin straps connected to the pockets at points above the surface of the cap.

4. A bathing cap having raised portions forming pockets to receive the ears of a bather, and an endless resilient band embracing the pockets and the bathing cap adjacent the periphery of the head receiving opening of said cap for creating pressure on the cap at such points to prevent the passage of water, straps connected with the pockets and overlapping the band to not only maintain the band in position but to create pressure on the ear pockets for forcing the cap adjacent the pockets in snug engagement with the head of a bather.

5. A bathing cap made of elastic materials having ear-receiving openings, ribs encircling the openings, a cover connected to the

ribs, a rib connected to each ear encircling rib, flush at one end with the cover and gradually decreasing in thickness towards the rear of the cap, and a rib connected to each 5 ear encircling rib at the front of the cap having its outer portion flush with the cover and decreasing in thickness until it substantially merges into the cap for aiding in preventing distortion of the pockets when the 10 cap is being applied to the head of a wearer.

6. A bathing cap having portions raised above the outer surface of the cap, and chin straps connected to the raised portions at points above said surface of the cap to cause the raised portions to exert an inward pressure on the cap and seal the cap against leakage. 15
